Albert M. Bank, Jersey City, N. J., assignor to
Sylvia Bank, Jersey City, N. J.

Application December 12, 1941, Serial No. 422,621

12 Claims. (Cl. 155—179)

This invention relates to furniture. It is particularly directed to foundations for seats or backs of upholstered chairs, sofas or the like articles of furniture.

An object of this invention is to provide in furniture of the character described, a spring support for the seat or back having highly improved spring edge construction.

Another object of this invention is to provide a spring foundation for the back of a chair, having highly improved spring edge at the top, sides and bottom thereof.

A further object of this invention is to provide in a strong and durable spring support of the character described which shall be relatively inexpensive to manufacture, easy to assemble, comfortable in use and withal practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown various possible illustrative embodiments of this invention,

Fig. 1 is a cross-sectional, elevational view of a frame for an upholstered chair provided with spring seat and back, embodying the invention;

Fig. 2 is a cross-sectional view taken on line 2—2 of Fig. 1;

Fig. 3 is a cross-sectional view taken on line 3—3 of Fig. 1;

Fig. 4 is a cross-sectional view taken on line 4—4 of Fig. 1;

Fig. 5 is a cross-sectional view taken on line 5—5 of Fig. 1;

Fig. 5a is a cross-sectional view taken on line 5a—5a of Fig. 1;

Fig. 6 is an enlarged, partial elevational cross-sectional view of the front end of the seat;

Fig. 7 is a front end view taken on the plane 7—7 of Fig. 6;

Fig. 8 is a perspective view of one of the brackets used to attach the rear ends of the zig-zag springs to the rear of the seat frame;

Fig. 9 is a perspective view of one of the brackets used to attach zig-zag springs to the back frame;

Fig. 10 is a perspective view of one of the straps for attaching the zig-zag springs to the interconnecting cross wire;

Fig. 11 is a view similar to Fig. 6, but illustrating a modified construction;

Fig. 12 is a top plan view of the structure shown in Fig. 11;

Fig. 13 is a view similar to Fig. 11, but illustrating a further modified construction;

Fig. 14 is a top view of a sofa seat frame embodying the invention;

Fig. 15 is a cross-sectional view taken on line 15—15 of Fig. 14; and

Fig. 16 is a cross-sectional view taken on line 16—16 of Fig. 14.

Referring now in detail to the drawings, 10 designates a frame for an upholstered chair comprising a spring seat foundation 11 and a spring back foundation 12. The spring foundation 11 comprises a seat frame 13 having side walls 14, a front wall 15 and a rear wall 16. The frame 15 13 is supported at the front on legs 17. The spring back foundation 12 comprises a back frame 18 having a top member 20, a bottom member 21, inner side members 22, and outer side members 23, which extend downwardly forming legs 24, to which the rear portion of a seat frame 13 is fixed.

Referring to the seat foundation 11, the same comprises a transverse, zig-zag shaped or sinuous supporting spring 25, disposed substantially parallel to the front wall 15 of the seat frame 13. The end loops or turns 27 of the spring 25 are bent back beneath the underside of the spring. Said spring may be slightly arched if desired. The ends of spring 25 are attached to the upper edges of the side walls 14 by means of brackets 26.

One of the brackets 26 is illustrated in Fig. 9 of the drawings. The same may be made of sheet metal and comprises a bottom wall 26a contacting the upper edge of wall 14. Said bottom wall 26a is formed with a central opening 26b, and a pair of openings 26c on opposite sides of the central opening. Extending from one end of the bottom wall is an upwardly and inwardly turned lip 26d formed with an opening 26e, aligned with opening 26b. Extending from the opposite end of the bottom wall 26a, are a pair of upwardly and inwardly turned ears 26f.

A pair of nails or other fastening members 29 are first driven through the openings 26c into the top edge of wall 14. The abutment loop 27 is then slipped in sideways between the ears 26d and 26f. Another nail or fastening member 30 is then driven through the registering openings 26e, 26b. The ears 26f are then hammered downwardly to grip the outer arm 27a of the abutment loop 27. The abutment loop cannot be accidentally moved sideways out of the bracket.

As shown in the drawings, for the purpose of illustration, spring 25 is spaced from front wall 15 about $\frac{1}{4}$ of the distance between wall 15 and 16, although the position of the spring 25 may be varied if desired.

Spring 25 may be lashed to the front wall 15 by a flexible guy 32, as shown in the drawings.

The guy 32 may comprise a sheet of burlap or other flexible or textile material. The sheet 32 is folded longitudinally about the spring 25, and the registering edge portions 32a thereof, are fastened to the upper edge of wall 15 by nails 33. The spring 25 is thus located between the folds of the sheet 32, and adjacent the fold thereof. The guy 32 prevents the spring 25 from being pulled away from the front wall 15, as will appear hereinafter, while permitting said spring to flex.

Supported on the rear wall 16 and the transverse spring 25, are a plurality of spaced springs 35, which may likewise be sinuous or zig-zag in shape. The rear ends of the springs 35 may be attached to the top edge of rear wall 16 by brackets 37, to be described in detail hereinafter.

At the rear end of each spring 35 is an inwardly bent abutment loop or turn 36 engaged within a bracket 37. Each spring 35 comprises a main arched portion 38 extending from the bracket 37 to the transverse spring 25. Thus, the forward end 39 of the arch portion 38 of each spring 35 is supported by the transverse spring 25. Extending upwardly and forwardly from the end 39 of each arched portion 38 is an inclined portion 40 having at its forward end, an end loop 41 bent beneath said portion 40.

The bracket 37 illustrated in Fig. 8 of the drawings may likewise be made of sheet metal, or the like material, and comprises a top wall 43 contacting the top edge of rear wall 16 and a wall 44 extending downwardly from wall 43 and contacting the outer surface of said rear wall 16 of the frame. Wall 44 is formed with a pair of openings, adjacent the lower end thereof, to receive nails 45 or other fastening means driven therethrough for attaching the bracket 37 to the frame.

Cut from the top wall 43 is a tongue 46, inclined upwardly and rearwardly from said top wall. Cut from the rear wall 44, is another tongue 47, inclined rearwardly. The arms of end loop 36 of spring 35 are engaged with the two tongues 46. Said tongues are then bent over the arms of loop 36. Arm 47 has an opening 48 to receive a nail or other fastening means driven into the side of frame wall 16. The advantage of the bracket 37 is that no nails have to be driven into the top thereof, as such operation would be difficult because wall 21 of the back frame is closed above rear wall 16 of the seat frame. A hammer may be worked sideways however, sufficiently to depress the tongue 46.

It will be noted that a part of the guy 32 is interposed between spring 25 and portions 39 of springs 35, thus eliminating noise. The portions 39 of spring 35 may be fixed to spring 25 by any suitable clips or hog's rings 45, piercing the cloth 32. The clips or rings 45 embrace crossing portions of the springs 35 and 25. Any suitable number of clips may be used for attaching springs 35 to the transverse spring, three such clips being shown for the purpose of illustration, for each of the springs 35.

It will be noted that the portions 40 of springs 35 may be freely flexed downwardly. Said springs are preferably tempered after the portions 40 are bent upwardly to the desired angle, so that said portions upon being flexed will return to normal angle when pressure is released.

The upper ends of spring portions 40 are disposed above the front wall 15. They may be interconnected by a cross wire 47 threaded through the loops 41. The transverse intercon-

necting wire 47 may be attached to said loops by straps 48, or any other suitable fastening means. The strap 48 may be made of a strip of easily bendable metal having loops 49 at the ends thereof.

To attach each loop 41 to the transverse wire 47, one end loop 49 of strap 48 may be first engaged with or threaded onto the outer arm 41a of said loop 41. The strap may then be wound around the other arm of the loop and around the wire 47 and then, the other end loop 49 may be threaded onto the outer arm of the loop 41, as illustrated in Figs. 6 and 7 of the drawings.

The seat may be upholstered in the usual manner, but preferably no padding is placed between the spring portion 40 and the guy 32, so as to permit free flexing of said spring portions. Spring portions 40 produce a soft and comfortable spring edge at the front of the seat.

20 The back foundation 12 comprises a pair of transverse sinuous or zig-zag shaped springs 50 and 51 supported on portions 22 of the back frame 18. Spring 50 is parallel to portion 21 of the back frame, and spaced therefrom about $\frac{1}{4}$ of the distance between portion 21 and 20 of said back frame. The spring 50 is substantially similar to spring 25 and the ends thereof are fixed within brackets 26 attached to portions 22 of the back frame.

25 Spring 50 is connected to the bottom portion 21 of the back frame by a guy 53, similar to the guy 32. The transverse spring 51 has a main central portion 51a from the ends of which there extends forwardly and outwardly, inclined free flexing portions 51b, similar to portions 40 of springs 35. The ends of portions 51a of spring 51 are attached to portions 22 of back frame likewise by brackets 26. Portions 51b of the spring 51 may be flexed rearwardly, and the ends thereof are substantially in alignment with portions 23 of the back frame. Portion 51a of spring 51 is connected to the top portion 20 of the back frame by a guy 55, likewise similar to the guy 32.

30 Supported by portion 51a of spring 51, and by spring 50, are a plurality of zigzag springs 56 extending up and down. Each has a central portion 56a from the upper ends of which there extends forwardly and upwardly inclined portions 56b, and from the lower ends of which there extends forwardly and downwardly inclined portions 56c. The ends 56d of portions 56a of springs 56 rest on the transverse springs 50 and 51, portions of the guys 53 and 55 being interposed either between springs 56 and springs 50 and 51. Springs 56 are attached to the springs 50, 51 by clips 60, such as hog rings or any other suitable fastening means.

35 As illustrated in the drawings, each of springs 50 and 51 are attached to the springs 56 by a plurality of said clips 60. Spring 50 and portion 51a of spring 51 may be slightly arched, if desired, or substantially straight. The outer turns of portions 51b of springs 51 may be bent backward, as at 51c. The outer turns of portions 50b may likewise be bent, as at 50d.

40 Attached to portions 22 of the back frame, somewhat below the brackets 26, which attach spring 51 to said portions of said back frame, are brackets 26 to which there are attached short zig-zag springs 65, likewise inclined upwardly and outwardly, similarly to portions 51b of spring 51. Each spring 65 may have a bent back abutment loop 66 at one end engaged within a bracket 26, and the outer end turn of said spring may

likewise be looped back as at 67. The outer ends of spring 56, 51 and portions 56b of springs 56, are interconnected by a member 70. Member 70 may be made of wire and has a top straight portion 71 attached to the loops 56d by straps 48, or any other suitable attaching means. Extending from portion 71 of member 70, are parallel arm portions 72 connected to loops 51c and 67, likewise by straps 48, or any other suitable clips or connectors.

Arms 72 extend substantially down to the middle of the back frame 18, and extending inwardly therefrom, are aligned horizontal portions 73 connected to substantially central portions of the end springs 56, by clips 75 or in any other suitable manner.

At the lower ends of spring portions 56c are bent back loop portions 56e interconnected by a connector member 80 made of wire, or in any other suitable material. Connector member 80 comprises a straight horizontal portion 81 connected to the loops 56e by straps 48 or any other suitable clips or abutment members. Extending from the outer ends of portion 81 are parallel arms 82 terminating short of portions 73 of connectors 70. At the inner ends of arms 82 are inwardly extending aligned portions 83 attached to the end springs 56 by clips or connectors 88.

It will now be understood that portions 56b, as well as portions 56c of springs 56, may be flexed rearwardly to produce a soft resilient back. Likewise, the end portions 51b of the springs 51, as well as the springs 65, provide resiliency at the sides of the back. In upholstering the back, it is preferable not insert any padding material beneath portions 56b and 56c of springs 56, or beneath portions 51b of spring 51, or beneath spring 65.

In Figs. 11 and 12 there is shown a modified construction. In said figures, the seat frame is provided with a transverse supporting spring 25 and a guy member 32, similar to that illustrated in Figs. 1 to 6 of the drawings. In Figs. 11 and 12, however, there is substituted for springs 35, springs 80 having portions 91, similar to portions 38 of springs 35, and similarly attached at their rear ends to the rear of the frame. Furthermore, the forward end of spring portion 91 rests on the transverse spring 25, likewise similar to spring 35.

However, there extends from the forward end of spring portion 91, an upwardly inclined spring portion 92 terminating above the front wall 15 of the seat frame, and extending from the upper end of spring 92, is a rearwardly and downwardly inclined spring portion 93 having a bent back loop 94 at its outer end contacting the spring portion 91 at a point spaced rearwardly from the forward end of said spring portion, and attached to said spring portion by clips 95, or in any other suitable manner. The apices of spring portions 92 and 93 are interconnected to a transverse wire 47, connected by clips 96, or in any other suitable manner.

In the modification illustrated in Fig. 13, there is substituted for the springs 35, a spring 100 having a portion 101 likewise similar to spring portion 39 of spring 35. The forward end of spring portion 101 rests on a transverse spring 25, similarly to springs 35, the guy 32, however being omitted.

Extending upwardly and forwardly from the front end of portion 101 is a spring portion 102 terminating above the front wall 15 of the seat frame. Extending downwardly and rearwardly

from the upper end of portion 102, is a spring portion 103, terminating at 104, substantially at the level of the upper edge of front wall 15. Fixed to the upper end of wall 15, and extending rearwardly therefrom is a strip spring 105 having a loop or eye 106 at its rear end, receiving the lower end 104 of spring portion 103.

In Figs. 14, 15 and 16 there is shown a seat frame 110, provided with a spring foundation 111 similar in every respect to the spring foundation shown in Fig. 1, with the exception that the transverse spring 25 being quite long, is supported at intermediate points by zigzag springs 112, disposed there beneath, and attached at their front and rear ends to the front and rear walls 15 and 16 of the frame. The spring foundation 111 has springs 35, the same as in Fig. 1, which are additionally supported by the intermediate springs 112 parallel thereto. The ends of springs 112 may be fixed to the frame by brackets 28.

If desired, the additional supporting springs 112 may be employed in chair seat frames, as well as in sofa seat frames.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A spring foundation comprising a frame, a spring connected to a pair of opposite walls of the frame, and being spaced from the other pair of opposite walls, and a plurality of springs each supported at one end on one of the second pair of opposite walls of the frame, and at an intermediate portion thereof on the first spring, each of said plurality of springs having at its opposite end, a free flexing portion extending toward the other of said second pair of opposite walls, and being spaced therefrom, and a border wire interconnecting the outer ends of said free flexing portions.

2. A spring foundation comprising a frame, a spring connected to a pair of opposite walls of the frame, and being spaced from the other pair of opposite walls, a plurality of springs each supported at one end on one of the second pair of opposite walls of the frame, and at an intermediate portion thereof on the first spring, each of said plurality of springs having at its opposite end, a free flexing portion extending toward the other of said second pair of opposite walls, and being spaced therefrom, and flexible guy means interconnecting the first spring to said other of said second pair of opposite walls.

3. A spring foundation comprising a frame, a transverse resilient support attached to a pair of opposite walls of said frame, and spaced from the other pair of opposite walls, and a plurality of resilient members extending generally transversely relative to said resilient support, and being supported on said resilient support, and having free flexing end portions spaced above one of said other pair of opposite walls and adapted to be flexed toward the frame, and a border wire interconnecting the outer ends of said free flexing portions.

4. A spring foundation comprising a frame, a transverse resilient support attached to a pair of opposite walls of said frame, and spaced from the other pair of opposite walls, a plurality of resilient members extending generally transversely relative to said resilient support, and being supported on said resilient support, and having free flexing end portions spaced above one of said other pair of opposite walls and adapted to be flexed toward the frame, a border wire interconnecting said free flexing portions, and guy means to connect said resilient support to one of said other pair of opposite walls of the frame.

5. A spring foundation comprising a frame, a pair of transverse, parallel springs connected at the ends thereof to a pair of opposite walls of said frame, and being disposed parallel to the other pair of opposite walls of the frame, and a plurality of springs disposed at right angles to said pair of springs, and attached at intermediate portions thereof to said pair of springs, and having at the ends thereof, free flexing portions spaced from said other pair of opposite walls of said frame, and a border wire interconnecting the outer ends of said free flexing portions.

6. A spring foundation comprising a frame, a pair of transverse, parallel springs connected at the ends thereof to a pair of opposite walls of said frame, and being disposed parallel to the other pair of opposite walls of the frame, a plurality of springs disposed at right angles to said pair of springs, and attached at intermediate portions thereof to said pair of springs, and having at the ends thereof, free flexing portions spaced from said other pair of opposite walls of said frame, and guy means to connect said pair of springs to said other pair of opposite walls of said frame.

7. A spring foundation comprising a frame, a pair of transverse, parallel springs connected at the ends thereof to a pair of opposite walls of said frame, and being disposed parallel to the other pair of opposite walls of the frame, a plurality of springs disposed at right angles to said pair of springs, and attached at intermediate portions thereof to said pair of springs, and having at the ends thereof, free flexing portions spaced from said other pair of opposite walls of said frame, and guy means to connect said pair of springs to said other pair of opposite walls of said frame, one of said pair of springs having at the ends thereof free flexing portions extending away from said frame.

8. A spring foundation comprising a frame, a pair of transverse, parallel springs connected at the ends thereof to a pair of opposite walls of said frame, and being disposed parallel to the other pair of opposite walls of the frame, a plurality of springs disposed at right angles to said pair of springs, and attached at intermediate portions thereof to said pair of springs, and having at the ends thereof, free flexing portions spaced from said other pair of opposite walls of said frame, guy means to connect said pair of springs to said other pair of opposite walls of said frame, and an additional pair of symmetrical springs attached to said frame, and disposed parallel to said free flexing end portions of said pair of springs.

9. A spring foundation comprising a frame, a

transverse zigzag spring attached to a pair of opposite walls of the frame and disposed in spaced relation to the other pair of opposite walls of the frame, and a plurality of zigzag shaped springs disposed generally at right angles to the first spring, means to attach the rear ends of said plurality of springs, to one of the other pair of opposite walls of said frame, means to attach intermediate portions of said plurality of springs

10 to said transverse spring, and said plurality of springs having free flexing end portions extending away from said frame and adapted to be flexed towards said frame.

11. A spring foundation comprising a frame, a transverse zigzag spring attached to a pair of opposite walls of the frame and disposed in spaced relation to the other pair of opposite walls of the frame, a plurality of zigzag shaped springs disposed generally at right angles to the first spring, means to attach the rear ends of said plurality of springs to one of the other pair of opposite walls of said frame, means to attach intermediate portions of said plurality of springs to said transverse spring, and said plurality of springs having free flexing end portions extending away from said frame and adapted to be flexed towards said frame, and means to interconnect the outer ends of said free flexing portions of said plurality of springs.

12. A spring foundation comprising a frame, a transverse zigzag spring attached to a pair of opposite walls of the frame and disposed in spaced relation to the other pair of opposite walls of the frame, a plurality of zigzag shaped springs disposed generally at right angles to the first spring, means to attach the rear ends of said plurality of springs to one of the other pair of opposite walls of said frame, means to attach intermediate portions of said plurality of springs

40 to said transverse spring, and said plurality of springs having free flexing end portions extending away from said frame and adapted to be flexed towards said frame, means to interconnect the outer ends of said free flexing portions

45 of said plurality of springs, and flexible means interconnecting the transverse spring to one of the first pair of opposite walls of said frame.

13. A spring foundation comprising a frame, a transverse zigzag spring attached to a pair of opposite walls of the frame and disposed in spaced relation to the other pair of opposite walls of the frame, a plurality of zigzag shaped springs disposed generally at right angles to the first spring, means to attach the rear ends of said plurality of springs to one of the other pair of opposite walls of said frame, means to attach intermediate portions of said plurality of springs to said transverse spring, and said plurality of springs having free flexing end portions extending away from said frame and adapted to be flexed towards said frame, means to interconnect the outer ends of said free flexing portions of said plurality of springs, and flexible means interconnecting the transverse spring to one of the first pair of opposite walls of said frame, said last means comprising a folded over sheet of textile material receiving the transverse spring within the fold thereof, and said sheet being attached to said one of said first pair of opposite walls of the frame.

ALBERT M. BANK.
